UNITED STATES PATENT OFFICE

104,617

DESIGN FOR A BEVERAGE COOLER

George V. Steffens, Clayton, Mo.

Application March 31, 1937, Serial No. 68,499

Term of patent 14 years

To all whom it may concern:

Be it known that I, George V. Steffens, a citizen of the United States, residing at the city of Clayton, in the county of St. Louis and State of Missouri, have invented a new, original, and ornamental Design for a Beverage Cooler, of which the following is a specification, reference being had to the accompanying drawing, forming a part thereof, in which—

The figure is a perspective view of a beverage cooler showing my new design.

The linings for color indicate that the lined surfaces are colored in contrast to the unlined portions. The end portion and the side portion

of the upper border opposite from those shown are of the same color as those shown, and the remaining portion of the end opposite from that shown is plain throughout.

The side of the beverage cooler opposite from that shown in the drawing is plain and in the same vertical plane, with the exception that said opposite side has an area with louver formation directly opposite from the louver formation on the side shown and of the same size and area.

I claim:—

The ornamental design for a beverage cooler as shown and described.

GEORGE V. STEFFENS.
